UNITED STATES PATENT OFFICE.

JAMES MARSHALL, OF LEEDS, ENGLAND.

QUADRUPLE-EXPANSION ENGINE.

SPECIFICATION forming part of Letters Patent No. 503,056, dated August 8, 1893.

Application filed August 31, 1892. Serial No. 444,679. (No model.) Patented in England September 2, 1891, No. 14,857.

To all whom it may concern:

Be it known that I, JAMES MARSHALL, a citizen of England, residing at the Steam Plow Works, Leeds, in the county of York, England, have invented certain new and useful Improvements in Quadruple-Expansion Engines, (for which I have obtained Letters Patent in Great Britain, dated September 2, 1891, No. 14,857,) of which the following is a specification.

In the specification to Patent No. 462,149, granted to me October 27, 1891, is described a construction of cylindrical tubular slide valve with packed piston parts and internal expansion valve for governing a pair of parallel cylinders of a compound or twin engine.

My present invention consists in the adaptation of a cylindrical tubular slide valve with an internal expansion valve of a construction similar to that described in the said patent to the regulation of the flow of steam into and out of single or double acting quadruple expansion engines with tandem cylinders. I will proceed to describe the construction and operation of the said valves with reference to the accompanying drawing, in which the figure is a vertical section of single acting quadruple expansion engines, with tandem cylinders, with the said valve apparatus applied thereto.

The letter A indicates the high pressure cylinder; A², the second cylinder; A³, the third, and A⁴ the fourth cylinder. This last cylinder is made double acting, the steam being made to pass from the top to the under side of the piston, in order by its further expansion, to take the load off the crank on the upstroke.

E is the lining to the valve chamber having rings of holes or slots communicating with the several annular passages in the body of the chamber.

F is the main cylindrical valve, and G is the expansion valve.

E² is the high pressure steam supply to the extension E' of the valve chamber E, from which it enters the extension F' of the main valve F, and is admitted to the cylinder A' by the ports Q' of the valve F when these communicate with the port L of the cylinder A' by means of the annular passage K'.

communicating with such port, the admission of steam being controlled by the expansion valve G.

In the position of the pistons and valves shown on the drawing, the piston S of the high pressure cylinder has just completed its stroke, and the steam is just about to pass into the second cylinder A² for which purpose the port Q² of the valve is in communication with the passage K', and is about to establish a communication through annular passage R and ports Q³ with passage K² and port L' of cylinder A². At the same time, the steam which has previously passed from cylinder A² to cylinder A³ is about to pass thence into cylinder A⁴ through port N, annular passage K³, port Q⁵, annular passage R', port Q⁶, annular passage K⁴ and port N' into cylinder A⁴ on the upper side of piston T'. At the same time also steam which had previously been admitted from the upper side to the under side of piston T' passes to the exhaust outlet U through port O and annular passages Q⁷ and K⁶.

On the valve F being moved into the opposite position to that shown on the drawing, high pressure steam is admitted to cylinder A' through ports Q' and passage K' as before described, while at the same time the steam passes from cylinder A² through port L', annular passage K², ports Q², passage R, port Q⁴, passage K³ and port N into cylinder A³ and at the same time also steam passes from the upper side of piston T' through port N', passage K⁴, port Q⁵, passage R', port Q⁶, passage K⁵ and port O to the under side of piston T'.

It will be evident that engines constructed as above described may be arranged either vertically, horizontally or inclined.

The present invention differs from the tripleexpansion engine described and claimed in my application, Serial No. 444,680, filed of even date herewith, in being a quadruple expansion engine which does not employ the steam chamber used in the triple expansion engine, into which steam from high pressure cylinders exhausts before passing to the intermediate low pressure cylinders.

Having thus described the nature of my invention and the best means I know for carrying the same into practical effect, I claim—

In quadruple expansion engines, the combination of a cylindrical main slide valve F having a port Q' controlled by a central cylindrical expansion valve and communicating with port L of high pressure cylinder A', ports Q², Q³, Q⁴ connected by annular passage R communicating with port L of cylinder A', port L' of second cylinder A², and port N of third cylinder A³, ports Q⁵ and Q⁶ connected by annular passage R' communicating with port N of third cylinder A³ and ports N' and O of cylinder A⁴, and a cylindrical valve chamber E having annular passage K' communicating with port L of cylinder A', passage K² communicating with port L' of cylinder A², passage K³ communicating with

port N of cylinder A³, passage K⁴ communicating with port N' of cylinder A⁴, and passages K⁵ K⁶ communicating respectively with port O of cylinder A⁴ and with exhaust port 20 U, substantially as described.

In testimony whereof I have signed my name to this specification, in the presence of two subscribing witnesses, this 8th day of August, A. D. 1892.

JAMES MARSHALL.
